UNITED STATES PATENT OFFICE

2,303,894

CONTROL FOR HEATING DEVICES

Ronald W. Olsen, Bloomfield, N. J., assignor to
 General Electric Company, a corporation of
 New York

Application April 29, 1941, Serial No. 390,964

14 Claims. (Cl. 236—1)

My invention relates to a control for a heating device, and although not limited thereto, it has particular application to a control for a stoker furnace wherein a response to variations in the fuel bed air flow resistance is desirable.

An object of my invention is to provide an improved automatic control arrangement for controlling the feeding of air and solid fuel to a heating device differentially upon variation in the fuel bed air flow resistance.

Another object of my invention is to provide an improved arrangement for automatically regulating the air flow through a fuel bed of variable thickness produced upon automatic operation of a fan means and automatically initiating joint operation therewith of a fuel feeding device only when the air flow is above a predetermined minimum, and in addition terminating operation of the fuel feeding device for a furnace in response to a predetermined fuel bed air flow resistance being introduced into the furnace.

A further object of my invention is to provide an improved stoker furnace control for preventing operation of a fuel feeding device in response to a movement of a constant combustion air flow control damper to a predetermined maximum open position.

A further object of my invention is to provide an improved furnace control arrangement for controlling the rate of fuel feed in response to the level of the outside temperature.

My invention will be more fully set forth in the following description referring to the accompanying drawing, and the features of novelty which characterize my invention will be pointed out in the claims annexed to and forming a part of this specification.

In the drawing, Fig. 1 illustrates a control for a stoker-fired furnace which is provided with embodiments of my invention, and Fig. 2 is a 40 sectional side elevation of the air flow control arrangement employed in the furnace control illustrated in Fig. 1.

In the arrangement illustrated in the drawing, which shows an air flow control for a stoker-fired furnace for maintaining a flow of combustion air to the furnace within predetermined limits for varying conditions of the fire in the furnace, I provide a fuel feed switch responsive to movement of the air flow control. Thus, the 50 stoker, or fuel feeding device, is deenergized when the air flow control device moves to a predetermined or relatively wide-open position. I may also provide a damper control arrangement in the furnace flue, the movement of which is respon-

sive to outdoor temperatures for further controlling, through the air flow control and fuel feed switch arrangement, the rate of fuel delivery to the furnace.

5 Referring more particularly to Fig. 1 of the drawing, I have provided a control for a heating device, such as a furnace indicated generally by the numeral 10, having a hopper 11 into which fuel, such as coal, may be placed, a retort 12 on which the coal is burned, and a fuel feeding tube 13 connected between the hopper and the retort for conducting the fuel from the hopper to the retort. The fuel may be forced through the fuel feeding tube 13 in any suitable manner, such as 15 through the movement of a fuel feeding screw 14. This screw may be rotated in any suitable manner, such as by a feed motor 15. Any other suitable arrangement may be provided for feeding fuel to the heating device. In order to provide an arrangement for conducting combustion air into the retort, a duct 16 is connected to the furnace and there is also provided any suitable air flow control arrangement for controlling the flow of air within predetermined limits, or for 20 maintaining a substantially constant flow of air into the retort for varying fire bed conditions. The air flow control which I employ with my invention is described and claimed in my co-pending application, Serial No. 390,961 and which 25 is assigned to the same assignee as this present invention. This air flow control is shown in detail in Fig. 2 and includes a damper 17 pivotally mounted on a shaft 18. The end of the damper extends through the intake end of the duct 16 and the duct is open on the sides and on the bottom. With such an arrangement, it is possible 30 to maintain a substantially constant flow of air into the retort for varying fire bed conditions. The air flow control which I employ with my invention is described and claimed in my co-pending application, Serial No. 390,961 and which 35 is assigned to the same assignee as this present invention. This air flow control is shown in detail in Fig. 2 and includes a damper 17 pivotally mounted on a shaft 18. The end of the damper extends through the intake end of the duct 16 and the duct is open on the sides and on the bottom. With such an arrangement, it is possible to maintain a substantially constant flow of air through the duct 16 for varying back pressure 40 conditions. Thus, the damper 17 will rotate around its pivot 18 against the biasing force produced by the weight member between the position indicated in Fig. 2 and the dotted line position 17', for varying conditions of system air flow resistance, in order to control the size of 45 the passageway in the duct. Therefore, for a relatively thick fire bed the damper will assume a position as shown in Fig. 2, while for a relatively thin fire the damper will assume a position as indicated by the dotted lines 17'. Any other suitable type of air flow control may also be provided, such as the one described in my co-pending application Serial No. 390,963, and which is 50 assigned to the same assignee as this present invention. In order to provide an outlet for the products of combustion from the furnace, a flue 55

18 is connected to the furnace and a fan 20 is placed therein in order to induce the draft, or to provide a pressure difference between the outside or intake end of the duct 18 and the end connected to the retort. Instead of employing an induced draft, a forced draft, a natural draft, or any other draft producing arrangement may be employed. A fan motor 21 is provided for rotating the fan 20.

In order that the fan and feed motors may be energized from a suitable source of power, a transformer 22 is provided having its primary winding connected to incoming lines 23 and 24. Its secondary winding 25 has one side thereof connected to an operating coil 26 of the relay indicated generally by the numeral 27 through a conductor 28. In order that the coil 26 may be energized when an increase in the heat of the fire is desired, I provide a suitable temperature responsive device, indicated generally by the numeral 29, and which may be placed in the room to be heated, or in any other suitable place. This thermostat has a bimetallic strip 30 with contacts 31 and 32 on the movable end thereof. Stationary contacts 33 and 34 are provided, the contact 33 being connected to one side of the secondary winding 25 through conductors 35 and 36, while the stationary contact 34 is connected to the opposite side of the transformer winding 25 through conductors 37 and 38. When the thermostat 29 calls for heat it will be seen that the bimetallic strip 30 will move to the left thus closing the contacts 31 and 33 so that the coil 26 will be energized through the circuit including one side of the transformer secondary winding 25, conductor 28, coil 26, bimetallic strip 30, contacts 31 and 33, and conductors 35 and 36. When the call for heat has been satisfied the thermostat will move to its open circuit position and then to the right so that the coil 26 will be short circuited through the contacts 32 and 34 so that the relay 27 may move to its inoperative position. The relay 27 is provided with a core 38 and contacts 39 and 40 which are operable to a circuit closing position when the core is picked up upon energization of the winding 26. The contacts 39 are provided in order to establish a holding circuit for the coil 26 through conductor 41, contacts 39 and conductor 42. When the contacts 40 are picked up the fan and fuel feeding motors will be energized. The energizing circuit for the fan motor may be traced from the line 24 through conductor 43, contacts 40, conductors 44 and 45, through the fan motor, conductor 46, conductor 47, back to the line 23. The circuit for the feed motor may be traced from line 24 through the conductor 43, contacts 40, conductor 44, a conductor 48, a switch 49 which is operated by movement of the damper 17 and the function of which will be described in more detail below, conductor 50, feed motor 15, conductors 51 and 41, back to the line 23.

Instead of employing a thermostat in the space to be heated for initiating the terminating operation of the fan and fuel feed motors, any other suitable condition response device, such as a thermostat responsive to furnace plenum temperature, or an aquastat responsive to boiler water temperature, may be employed.

As described above and in my above first-mentioned copending application S. N. 390,961, the air flow control arrangement will move so as to maintain a substantially constant flow of air into the retort for varying conditions of the fire bed. Thus, if the fire bed is very light it will provide

only a relatively low resistance to the flow of air and the damper 17 need only be open a slight amount in order to allow a predetermined rate of air flow into the retort. However, if the fuel bed is very thick it will provide a much higher resistance to the flow of air so that the damper 17 must move to a relatively wide open position in order to maintain the same rate of air flowing to the retort. In order to control the feed motor in response to fuel bed thickness any suitable circuit breaker arrangement, such as the switch 49, may be provided, the operation of which is responsive to movement of the constant air flow control arrangement which is employed. The switch will remain closed when the fan motor is running and the fire bed thickness, or resistance, is below any predetermined maximum amount, but it opens when the air flow control assumes its position to give an approximately maximum opening, which is the position shown in Fig. 2, that is, when the system resistance is relatively high or when the fire bed thickness has reached this predetermined maximum amount. The switch 49 may be of any suitable type, such as a mercury switch and since it is supported on the shaft 18, it may be made to disconnect the feed motor circuit when the shaft has assumed any predetermined position. The switch 49 has contacts on either side thereof which may be connected to the conductors 48 and 50, a pool of mercury 52 in the interior of the switch, and a central portion which has a hole therein. When the hole is below the surface of the mercury it will flow therethrough and make a closed circuit between the switch contacts. The switch need only be suitably placed on the shaft 18 so that the hole 53 will be above the level of the mercury when the damper has assumed its position of approximately maximum opening, as shown, and will be below the level and remain so within any predetermined range of damper movement. Thus, the switch will close its contacts when the damper has moved from the position shown in Fig. 2 to a position as indicated by the dotted lines 54 and will remain closed during movement of the damper between this position and the dotted line position 17', or minimum opening position. It will be noted that a mercury switch of the balanced disk or wafer type, which may be mounted on an axis passing through its center of gravity, is a desirable type to employ when an air flow control of the type described above is employed, since movement of the switch with the damper will not change the center of gravity of the damper counter weight combination. Thus, through the air flow control, the fuel feed motor may be turned on and off in order that no new coal will be fed into the furnace if the bed has reached a predetermined maximum thickness, this thickness being any suitable value, such as that which the fan can just handle with the damper almost wide open. Thus, operation of the fuel feeding device is prevented when the damper is operated to a predetermined maximum open position.

It will also be noted when an air flow control is employed as shown in Fig. 2, which is biased so that it assumes a position of substantially maximum opening when the fan is deenergized, that at the moment the thermostat calls for heat the fan will be actuated first and the fuel feeding motor will be actuated after the damper 17 has moved into the range between the positions indicated by the dotted lines 54 and 17'. With

such a system there will always be assured an adequate supply of combustion air before coal is fed into the retort.

The control system may also be provided with an arrangement so that the rate of fuel feed may be regulated in response to variations in the level of the temperature outside. Thus, I may provide a damper 55 in the flue, the movement of which may be made responsive to outdoor conditions. In order to accomplish this a bellows 56 may be provided which has a bulb 57 responsive to outdoor temperature conditions. A rod 58 and a suitable linkage 59 are provided so that movement of the bellows may cause corresponding movement of the damper 55. When the damper 55 has moved to a relatively closed position it will be in effect throttling or reducing the effectiveness of the fan 20, as it will be increasing the back pressure which the fan motor must overcome. Conversely, if the damper 55 is moved to a wide-open position it will present substantially no impediment to the movement of the products of combustion through the flue. I have found that by moving the damper 55 from a wide-open position to a position which throttles the fan motor, I am able to control the rate at which the fuel will be fed from the hopper to the retort. The rod and linkage are, therefore, connected so that the damper is wide open when the outdoor temperature is relatively cold, while the damper will be moved to a relatively closed position during relatively warm weather. When the damper 55 is nearly closed, damper 17 will open to a relatively wide open position to try to maintain the air flow constant and thus will cycle the fuel feed motor on and off, thus reducing the total flow of fuel. In this manner I may control the rate of fuel feed to the furnace by varying the position of the damper 54, since this in turn controls the position of the air flow control damper 17. Such a control of the rate of fuel feed is particularly desirable during mild seasons of the year, since in the spring and the fall a lesser amount of fuel feed is needed than in the cold weather. Thus, the bellows may be set so as to throttle the fan in the spring and the fall and still provide relatively no impediment to its during the relatively cold season of the year.

Although I have shown and described particular embodiments of my invention, I do not desire to be limited to the particular embodiments described, and I intend in the appended claims to cover all modifications which do not depart from the spirit and scope of my invention.

What I claim as new and desire to secure by Letters Patent of the United States is:

1. A control for a furnace including a fuel feeding device, a duct for introducing combustion air into said furnace, fan means for producing a flow of air through said duct, air control means for maintaining a substantially constant quantity of air flow through said duct for varying conditions within said furnace, means for initiating operation of said fan means when an increase in the amount of heat from said furnace is desired, means responsive to movement of said air control means to predetermined positions for initiating and terminating operation of said fuel feeding means, and means responsive to changes in outdoor temperature for varying the effectiveness of said fan means so as to control the rate of fuel feed to the furnace in response to outdoor temperatures.

2. A control for a furnace including a fuel feed-

ing device, a duct for introducing combustion air into said furnace, fan means for producing a flow of air through said duct, air control means for producing a substantially constant quantity of air flow through said duct for varying fire conditions within said furnace, flue means connected to said furnace, means for initiating operation of said fan means when an increase in the amount of heat from said furnace is desired, means responsive to movement of said air control means to predetermined positions for initiating and terminating operation of said fuel feeding means, and damper means within said flue, said damper means being movable in response to variations in outdoor temperature for controlling the rate of feed of said fuel feeding means.

3. A control for a furnace including a fuel feeding device, a duct for introducing combustion air into said furnace, fan means for producing a flow of air through said duct, air control means for producing a substantially constant quantity of air flow through said duct for varying fire conditions within said furnace, flue means connected to said furnace, means for initiating operation of said fan means when an increase in the amount of heat from said furnace is desired, means responsive to movement of said air control means to predetermined positions for initiating and terminating operation of said fuel feeding means, and damper means within said flue, said damper means being movable in response to variations in outdoor temperature for controlling the rate of feed of said fuel feeding means.

4. In combination, a combustion heating device having a fuel bed, stoker means for feeding fuel to increase the thickness of said fuel bed, independently operable fan means for producing a flow of combustion air through said fuel bed dependent upon the thickness thereof, an automatic flow responsive damper movably mounted in the path of said air flow for maintaining the flow within predetermined limits and having biasing means for maintaining said damper in a predetermined position until said air flow increases above the minimum limit, an automatic stoker control device responsive to movement of said damper to said predetermined position for preventing operation of said stoker means, and automatic control means having connections for independently operating said fan means and having other connections under the control of said stoker control device for operating said stoker means jointly with said fan means only upon movement of said damper from said predetermined position.

5. In combination, a combustion heating device having a fuel bed, stoker means for feeding fuel to increase the thickness of said fuel bed, separately operable fan means for producing a flow of combustion air through said fuel bed dependent upon the air flow resistance thereof, a damper having automatic operating means responsive to the air flow through said fuel bed produced upon operation of said fan means when the flow resistance of said fuel bed is within a predetermined range for maintaining the rate of said air flow substantially constant upon variation in the flow resistance of said fuel bed within said predetermined range, a stoker control device operated by said automatic means for preventing operation of said stoker means when the flow resistance of said fuel bed exceeds said range, and automatic control means having connections for independently operating said fan means and having other connections under the control of said

stoker control device for operating said stoker means jointly with said fan means only when the flow resistance of said fuel bed is within said predetermined range.

6. In combination, a furnace having a fuel bed, stoker means for feeding fuel to increase the thickness of said fuel bed, a fan for producing a flow of combustion air through said fuel bed dependent upon the thickness thereof, a damper having automatic operating means responsive to changes in the velocity of air flow through said fuel bed produced upon operation of said fan for positioning said damper intermediate predetermined open and closed positions to maintain a substantially constant air flow through said fuel bed upon variation in the thickness thereof, and condition responsive means for controlling joint operation of said fan means and said stoker means including means for preventing operation of said stoker means jointly with said fan means when said damper is operated to said predetermined open position.

7. In combination, a combustion heating device having a fuel bed, stoker means for feeding fuel to increase the thickness of said fuel bed, separately operable fan means for producing a flow of combustion air through said fuel bed dependent upon the thickness thereof, means including a damper biased to a predetermined open position and having cooperating air flow directing means for varying the position of said damper upon operation of said air flow producing means to maintain the rate of air flow through said fuel bed substantially constant upon variation in the thickness of said fuel bed, stoker control switch means operated upon movement of said damper to said predetermined open position for preventing operation of said fuel feed means, and automatic control means having connections for operating said fan means and having other connections under the control of said stoker control switch means for operating said stoker means jointly with said fan means only upon movement of said damper from said predetermined open position.

8. In combination, a combustion heating device having a fuel bed, stoker means for feeding fuel to increase the thickness of said fuel bed, separately operable fan means for producing a flow of combustion air through said fuel bed dependent upon the thickness thereof, means including a centrally pivoted damper having balancing means for biasing said damper to the open position and having cooperating air flow directing means for varying the position of said damper upon operation of said air flow producing means to maintain the rate of air flow through said fuel bed substantially constant upon variation in the thickness of said fuel bed, balanced switch means operated upon movement of said damper to said open position for preventing operation of said stoker means, and automatic control means having connections for operating said fan means and having other connections under the control of said balanced switch means for operating said stoker means jointly with said fan means upon movement of said damper from said predetermined open position.

9. In combination, a combustion heating device having a fuel bed, stoker means for feeding fuel to increase the thickness of said fuel bed, separately operable fan means for producing a flow of combustion air through said fuel bed dependent upon the air flow resistance thereof, a damper having automatic operating means responsive to

the air flow produced upon operation of said fan means for maintaining the rate of said air flow substantially constant upon variation in the flow resistance of said fuel bed within a predetermined range, separate air flow control means for controlling said air flow to predetermine said range, a stoker control device operated by said automatic means for preventing operation of said stoker means when the flow resistance of said fuel bed exceeds said range, and automatic control means having connections for operating said fan means and having other connections under the control of said stoker control device for operating said stoker means jointly with said fan means when the flow resistance of said fuel bed is within said predetermined range.

10. In combination, a combustion heating device having a fuel bed, stoker means for feeding fuel to increase the thickness of said fuel bed, separately operable fan means for producing a flow of combustion air through said fuel bed dependent upon the air flow resistance thereof, means including a damper biased to a predetermined position and having operating means for varying the position of said damper upon operation of said air flow producing means to maintain the rate of air flow through said fuel bed substantially constant upon variation in the flow resistance of said fuel bed within a predetermined range, separately operable damper means for restricting the flow of air through said fuel bed to predetermine said range, stoker control switch means operated upon movement of said damper to said predetermined position for preventing operation of said stoker means, and automatic control means having connections for operating said fan means and having other connections under the control of said stoker control switch means for operating said stoker means jointly with said fan means upon movement of said damper from said predetermined open position.

11. In combination, a furnace having a fuel bed, stoker means for feeding fuel to increase the thickness of said fuel bed, separately operable fan means for producing a flow of combustion air through said fuel bed dependent upon the air flow resistance thereof, automatic means for energizing and deenergizing said fan means and having connections for controlling the joint operation of said stoker means with said fan means, a damper having automatic operating means responsive to the flow of air through said fuel bed produced upon operation of said fan for positioning said damper intermediate the open and closed positions thereof for maintaining said flow of air through said fuel bed substantially constant upon variation in the flow resistance of said fuel bed within predetermined limits, and switch means for controlling said connections responsive to movement of said damper to the maximum open position for preventing operation of said stoker means, said automatic operating means being biased to move said damper to said maximum open position when said fan is inactive.

12. In combination, a furnace having a fuel bed, stoker means for feeding fuel to increase the thickness of said fuel bed, control means for controlling the operation of said stoker means and operating means for said control means including an automatic flow responsive damper for maintaining the flow of combustion air through said fuel bed substantially constant upon variation of the fuel bed flow resistance within a predetermined range, and means responsive to variations in the outdoor temperature for separately

varying the flow of air through said fuel bed to predetermine said range.

13. In combination, a furnace having a fuel bed, stoker means for feeding fuel to increase the thickness of said fuel bed, separately operable fan means for producing a flow of combustion air through said fuel bed, a damper having automatic operating means responsive to the air flow produced upon operation of said fan means for maintaining the rate of said air flow substantially constant upon variation in the flow resistance of said fuel bed within a predetermined range, means responsive to variations in the outdoor temperature for separately varying the rate of air flow through said fuel bed to predetermine said range, and means responsive to movement of said damper to the maximum open position for preventing operation of said stoker means when the flow resistance of said fuel bed exceeds said range.

14. In combination, a furnace having a fuel

bed, stoker means for feeding fuel to increase the thickness of said fuel bed, a fan for producing a flow of combustion air through said fuel bed, condition responsive means for starting and stopping operation of said fan, means including a centrally pivoted damper having balancing means for biasing said damper to the open position and having cooperating air flow directing means for varying the position of said damper upon operation of said fan to maintain the rate of air flow through said fuel bed substantially constant upon variation in the flow resistance of said fuel bed within a predetermined range, a separately movable damper having operating means responsive to variations in outdoor temperature for varying the effectiveness of said fan to predetermine said range, and balanced switch means operated upon movement of said first damper from said open position for initiating operation of said stoker means.

RONALD W. OLSEN.
